CLAIM

The ornamental design for a computer generated image for a display panel or screen, as shown and described.

DESCRIPTION

FIG. 1 is a first embodiment of a computer generated image for a display panel or screen showing our new design.

FIG. 2 is a second embodiment of a computer generated image for a display panel or screen showing our new design.

FIG. 3 is a third embodiment of a computer generated image for a display panel or screen showing our new design.

FIG. 4 is a fourth embodiment of a computer generated image for a display panel or screen showing our new design.

FIG. 5 is a fifth embodiment of a computer generated image for a display panel or screen showing our new design.

FIG. 6 is a sixth embodiment of a computer generated image for a display panel or screen showing our new design.

FIG. 7 is a seventh embodiment of a computer generated image for a display panel or screen showing our new design.

The display panel and screen portions in broken lines are for illustrative purposes only and form no part of claimed design.
